UNITED STATES PATENT OFFICE.

ARTHUR A. MERRITT, OF WORCESTER, MASSACHUSETTS, ASSIGNOR TO WILLCOX & GIBBS SEWING MACHINE CO., OF NEW YORK, N. Y., A CORPORATION OF NEW YORK.

SEAM.

1,219,023.

Specification of Letters Patent. Patented Mar. 13, 1917.

Application filed January 29, 1910. Serial No. 540,826.

To all whom it may concern:

Be it known that I, ARTHUR A. MERRITT, a citizen of the United States, and a resident of Worcester, Massachusetts, have invented 5 a new and useful Improvement in Seams, which invention is fully set forth in the following specification.

The improved seam constituting the present invention is particularly designed for 10 and adapted to the joining together of superimposed and abutting edges of fabrics, particularly cut-knit goods, and loosely woven goods, such for example, as used in making muslin underwear, ladies' shirt-waists, etc.; but the seam may also be employed to advantage with other kinds of fabrics and for ornamental and other purposes.

The invention will be most readily understood by reference to the illustration thereof 20 in the accompanying drawing, wherein—

Figure 1 is a plan view of the seam made with six threads, and

Figs. 2 and 3 are sections on lines 2—2 25 and 3—3, respectively, of Fig. 1.

The seam is illustrated as joining two abutting ends or edges of fabric 26 and 27. Surface threads 28 and 29 loop back and forth in the opposite faces of the seam across 30 the line of abutment of the edges of the fabric. Loops in two locking threads 30 and 31 extend through fabric 26 and loops in two locking threads 32 and 33 extend through fabric 27. As clearly shown, the 35 thread of each loop *i* in thread 28 passes through two of the loops *j* in thread 30 and through two of the loops *k* in thread 31, and the thread of each loop *j* and *k* passes through two loops *i*. The same is true of 40 loops *m* in thread 28 with relation to loops *n* in thread 33 and loops *o* in thread 32; of loops *p* in thread 29 with relation to loops *q* in thread 33 and *r* in thread 32; and of loops *s* in thread 29 with relation to loops *t* in 45 thread 30 and loops *u* in thread 31.

The advantages of the seam as above described are apparent, but by way of example the following are mentioned:

The seam is neat, compact and attractive 50 in design, and may, if desired, be used solely for decorative purposes. It is capable of being made by a single operation of a suitable machine. It provides a decorative and secure finish, binding and covering over the 55 abutted or lapped edges of fabric, and thus

prevents raveling of cut or raw edges, and the cut thread-ends from sticking up and marring the seam. As shown the width of the seam may be such as to take a wide hold, particularly upon loosely woven fabrics, by 60 the presence of the intermediate locking threads (preferably in pairs) such as 31, 32, so that each thread added may have an anchorage in its respective fabric edge to provide holding power as may be desired. The seam described may be used for ornamental purposes along the edge or edges of one fabric or a plurality of fabrics. When so used, each locking thread becomes an effective holder and covering element for the 65 edge or edges and prevents raveling of a knitted fabric, or the pulling away of a woven fabric by the slipping of its filling strands off cut ends of its warping strands, or vice versa. As will also be apparent, this 70 seam may be applied to superimposed and overlapped pieces or ends of fabrics.

A further important advantage of this seam is that it effects a union of two abutting edges of fabric while leaving a perfectly flat surface at the seam. The usual objectionable seam ridge is obviated and the thickness through the seam may be practically the same as that of the fabric itself. In this connection it is to be understood that with the proper tension of the threads, the latter sink into the soft or yielding surface of the fabric, a characteristic not shown in the drawing and which it would be difficult, if not impossible, to adequately illustrate 80 85 therein.

It may be found desirable to sometimes form the threads in the interlocking relationship described, in the absence of fabric, as for example in the "chaining off" operation of a machine capable of forming the 90 seam. The chain or seam thus formed independent of fabric may have a variety of uses.

It is apparent that a better finish and more 100 satisfactory result, both in joining two or more edges of fabric and for ornamental purposes, may be obtained by applying the seam, in any of its forms, to machine-trimmed or accurately cut edges. To this end it would be desirable to provide, in the mechanism for forming the seam, a mechanically operated trimmer or suitable cutting device, efficient forms of which are well 110 known.

It is the intention that the seam, in any of its forms, shall be made by a single operation of a suitable sewing machine, in which the locking threads may be introduced by 5 needles and the surface threads by loopers. But it is to be understood that no restriction or limitation is imposed requiring these threads to be incorporated in the seam by the use of needles or loopers, or as to the 10 character of the mechanism by which the seam is to be formed.

What is claimed is:

1. In a thread-structure, the combination of a surface thread looped back and forth in 15 one face of the structure, a second surface thread looped back and forth in the other face of the structure, a locking thread looped back and forth in interlocking engagement with the loops in both surface 20 threads along one edge of the structure, and a second locking thread looped back and forth in interlocking engagement with loops in both surface threads along the other edge of the structure, each of said four threads 25 serving to secure the loops of the threads with which it interlocks, and one or more additional locking threads located between the two aforesaid locking threads and disposed similarly to the latter with relation to the 30 two surface threads.
2. In a thread-structure, the combination of a surface thread looped back and forth in one face of the structure, a second surface 35 thread looped back and forth in the other face of the structure, a locking thread looped back and forth in interlocking engagement with the loops in both surface threads along one edge of the structure, and a second locking thread looped back and forth in interlocking engagement with loops in both surface 40 threads along the other edge of the structure, the thread of each loop in both surface threads passing through two loops in a locking thread and the thread of each 45 loop in both locking threads passing through two loops in a surface thread, each of said four threads serving by such interlocking of loops to secure the loops of the threads with which it interlocks, and one or more additional locking threads located between the two aforesaid locking threads and disposed similarly to the latter with relation to the 50 two surface threads.

3. In a seam, the combination with fabric, of a surface thread looped back and forth 55 against the surface of the fabric in one face of the seam, a second surface thread looped back and forth against the surface of the fabric in the opposite face of the seam, a locking thread looped back and forth 60 through the fabric in interlocking engagement with the loops in both surface threads along one edge of the seam, and a second locking thread looped back and forth in interlocking engagement with loops in both 65 surface threads along the other edge of the seam, each of said four threads serving to secure the loops of the threads with which it interlocks, and one or more additional locking threads located between the two aforesaid 70 locking threads and disposed similarly to the latter with relation to the two surface threads.

4. In a seam, the combination with fabric, of a surface thread looped back and forth 75 against the surface of the fabric in one face of the seam, a second surface thread looped back and forth against the surface of the fabric in the opposite face of the seam, a locking thread looped back and forth 80 through the fabric in interlocking engagement with the loops in both surface threads along one edge of the seam, and a second locking thread looped back and forth in interlocking engagement with loops in both 85 surface threads along the other edge of the seam, the thread of each loop in both surface threads passing through two loops in a locking thread and the thread of each loop in both locking threads passing through two 90 loops in a surface thread, each of said four threads serving by such interlocking of loops to secure the loops of the threads with which it interlocks, and one or more additional locking threads located between the two aforesaid 95 locking threads and disposed similarly to the latter with relation to the two surface threads.

In testimony whereof I have signed this specification in the presence of two subscribers 100 witnesses.

ARTHUR A. MERRITT.
